UNITED STATES PATENT OFFICE

123,321

DESIGN FOR A VEHICLE

Clarence D. Gill, Trenton, N. J.

Application May 17, 1940, Serial No. 92,433

Term of patent 14 years

To all whom it may concern:

Be it known that I, Clarence D. Gill, a citizen of the United States, residing in Trenton, Mercer county, State of New Jersey, have invented a new, original, and ornamental Design for a Vehicle, of which the following is a specification, reference being had to the accompanying drawings, forming a part thereof, and in which:

I claim:

The ornamental design for a vehicle, substantially as shown and described.

CLARENCE D. GILL.
